FREIGHT-HANDLING APPARATUS

Application filed October 3, 1929. Serial No. 397,107.

This invention relates to freight handling apparatus.

It is among the objects of the present invention to provide a new and improved apparatus for handling freight. The apparatus is particularly designed for use in handling pre-packed containers, the arrangement being such that the container may be packed in a store or factory and may be handled by our improved apparatus without unpacking until it has reached its destination. Such use of the present invention eliminates the necessity of careful loading of various packages into a freight car or truck and subsequent unloading of the individual packages. The packages may be packed once and finally within the container and the container is handled by the present invention without disturbing the packing of the container.

20 A further object of the present invention is to provide a novel and improved freight-handling apparatus, which includes the provision on a vehicle of a movable trackway which may be operated to lift the container and allow it to slide over the trackway to be deposited upon an adjacent platform.

25 A further object of the present invention is to provide in combination with a vehicle, supplementary side supporting means for the vehicle so that the weight of the container may be carried by the vehicle until the container is lowered upon a suitable platform, the side supports being such that tilting of the vehicle due to the weight of the container, will be avoided.

30 Other objects of the present invention include the novel combination and interrelation of parts, whereby the whole forms a novel, simple and improved device particularly adapted for the handling of large containers with minimum effort.

35 Other objects and features of the present invention will be apparent from a consideration of the following specification taken in conjunction with the accompanying drawings, in which

40 Figure 1 is a plan view partly in section, illustrating one form of the present invention;

Fig. 2 is a vertical sectional view taken on lines 2—2 of Fig. 1;

Fig. 3 is an end elevation showing the container removed from the vehicle and ready for deposit upon a platform;

Fig. 4 is a modified form of the invention showing its adaptation for rail cars.

Referring more particularly to Figs. 1 to 3 of the drawings, it will be seen that the invention includes a suitable truck including a body 10 which may be supported in any desired manner upon the wheels 11. Considering the present invention, it will be understood that the device is not confined to the specific truck embodying the wheel assembly herein shown. The wheels herein illustrated are merely diagrammatically shown to indicate the general type of truck used. The truck herein shown is preferably in the form of a trailer but it will be understood that the invention may be used upon an auto vehicle or upon a rail car, as illustrated in Fig. 4, if desired.

The body of the truck is preferably of skeleton formation including corner channel members 12 together with suitable longitudinally extending bed members 13 and transversely extending end members 14, the upper ends of the channel members 12 being joined by a complete or partial top as indicated at 15. Although the preferred embodiment of the invention herein shown discloses merely a skeleton form of the vehicle body, it will be understood that it is within the scope of the invention to build a completely closed body including a closed top, if desired.

Supported in association with the channel members 12, there is provided externally threaded rotatable corner posts 16, the lower ends of which are provided with bevel gears 17 which co-operate with gears 18 carried by the extremities of transversely extending base shafts 19. The base shafts are rotated by a centrally positioned longitudinally extending operating shaft 20, which extends beyond the extremities of the body for manipulation by a suitable tool. The operating shaft 20 is provided with gears 21 which enmesh with the gears carried by the inner ends of the transverse shafts 19, whereby rotation of the

operating shaft 20 will provide for rotation of the corner posts 16.

Supported by and movable over each pair of corner posts, there is provided a track supporting plate 22, which includes internally threaded collars 23 through which the posts 16 extend, whereby rotation of the posts in response to the rotation of the operating shaft 20 will vertically move the track plate 22. Mounted upon the track plate 22, there is provided a plurality of pairs of vertically spaced rollers 24, between which there is mounted a freely slideable track member 25. The track member includes a flange receivable between the rollers 24 and an inwardly extending flange which terminates in a vertical track upon which rollers 26 of the container 27 are mounted.

The container 27 includes the centrally positioned horizontally spaced rollers 26 associated with each end wall thereof. The container 27 is preferably a completely sealed container unit, by the use of which a complete side wall and top for the vehicle are not required. In some instances, however, the container may take the form of a simple shipping crate, and, if desired, may be used in conjunction with the substantially open vehicle here shown or in conjunction with a completely closed vehicle. As indicated in the drawings, the container 27 includes end doors 28, which are hingedly associated with the container, the arrangement being such that the container provides a self-contained unit which may be readily packed and sealed and which may be carried by the present apparatus and manipulated thereby to be delivered at its destination without disturbing its contents.

In the operation of the present device, by referring to Fig. 3 it will be seen that the container may be packed and positioned on a delivery platform. The vehicle is then moved parallel with the container and by rotation of the operating shaft 20, the corner posts 16 will be rotated whereby the track carrying plate will move downwardly in response to its threaded connection with the corner posts. When the desired downward movement of the track plate is accomplished, the tracks are moved outwardly to be positioned under the rollers 26 of the container. Reverse rotation of the operating shaft 20 then moves upwardly the track carrying plate and the tracks to engage the rollers and lift the container. With the container in lifted position, it may be readily rolled upon the track until one of the rollers 26 strikes the inner stop 29 of the track shown in Fig. 3. Further movement of the container within the body will cause the track to move upon its rollers 24 until the container is fully received within the vehicle, in which position it may be locked by suitable means and the vehicle may then be driven to the desired destination of the container.

For preventing tilting of the vehicle when the weight of the container is carried by the extended track, as shown in Fig. 3, the vehicle is provided with end supporting members 30 which are telescopic, the arrangement being such that the ground-engaging portion 31 of them may be received within the upper portion to permit the support to be swung vertically with the vehicle. 70

The vehicle further preferably includes stirrups 32 secured to the under side thereof and adapted to support a horizontally slideable bar 33. At one end of this bar 33 a slot 33' is provided forming a pair of spaced members between which, at their ends, a ground engaging element 34 is pivoted. In Fig. 3 a portion of the bar 33 has been broken away to clearly show this slot 33' and which slot is of sufficient size to permit the ground engaging element 34 to be swung on its pivot and housed horizontally within the confines of the bar 33, the arrangement being such that when not in use the element 34 may be raised so as to be housed within the bar 33 and the whole then moved horizontally and inwardly 80 under the vehicle to be supported in collapsed position by the stirrups 32. 90

When it is desired to unload the container, the side supports are swung to ground-engaging position, thus insuring the vehicle against tilting, and the container is rolled outwardly on the tracks. When the container rollers 26 strike the outward stop 35 of the track 25, the track will be moved outwardly from its rollers 24 to the desired position and with the container thus supported by the vehicle over a receiving platform, the operating shaft 20 is rotated to move downwardly the track carrying plate whereupon the container is lowered upon the platform and the track 100 is therefore further lowered to release the stop 35 from the roller 26. After release, the track is moved inwardly to be received within the vehicle and the side supports are folded, whereby the vehicle is ready for further travel. 105

For retaining the tracks in proper alignment with their rollers during the outward support of the retainer, a pair of pivoted track supporting elements 36, is provided 115 which are movable at an angle with respect to the vehicle to underlie the tracks when they are in extended position and to provide an external support for the under side of the tracks. Thus as indicated in Fig. 3, they 120 assist in supporting the tracks to prevent the load carried by the end thereof to disturb the tracks and to relieve the rollers 24 of a portion of the strain which would normally be directed to them. 125

Referring more particularly to Fig. 4, it will be seen that the present device is adapted for use in connection with rail cars in which instance the rail cars may be centrally divided, each rail car being adapted to receive 130

and handle two or more of the containers. The track structure, track carrying plate, the posts, and side supports, as well as the track supports, are all provided, as indicated by similar numbers in Fig. 4, to those used in connection with Figs. 1 to 3. It will be understood that this form of the invention is not confined to any specific number of the container handling means, but the car may be divided to provide any requisite number.

From the foregoing it will readily be seen that the present invention provides a novel, simple and improved structure for the handling of merchandise without requiring its packing and unpacking intermediate the shipping point and destination. It will further be seen that the present invention is not confined to the specific structural details herein presented but that numerous changes, modifications and the full use of equivalents may be resorted to without departing from the spirit or scope of the present invention as outlined in the appended claims.

In the use of the present invention on rail cars, it will be seen that the receptacles are interchangeable so that after shipment of a car including two receptacles to a certain point, the receptacles may thereafter be separately routed without requiring the usual unpacking of the car. The receptacle is simply taken from one car and placed upon another. The receptacles and cars are adapted to be standard equipment so that the receptacles may be interchanged between railroads in the manner of the present-day railroad car.

What is claimed is:

1. A freight handling apparatus, including a vehicle, and a plurality of sliding tracks carried by said vehicle for engaging rollers carried by a container to permit said container to be moved on said tracks into and out of said vehicle.

2. A freight handling apparatus, including a vehicle, a plurality of sliding tracks carried by said vehicle for engaging rollers carried by a container to permit said container to be moved on said tracks into and out of said vehicle, and means for vertically moving said tracks to engage or disengage the rollers of said container.

3. A freight handling apparatus, including a vehicle, a plurality of sliding tracks carried by said vehicle for engaging rollers carried by a container to permit said container to be moved on said tracks into and out of said vehicle, and means for vertically moving said tracks to engage or disengage the rollers of said container, said means including a movable track carrying plate associated with said vehicle.

4. A freight handling apparatus, including a vehicle, a plurality of sliding tracks carried by said vehicle for engaging rollers carried by a container to permit said container

to be moved on said tracks into and out of said vehicle, and means for vertically moving said tracks to engage or disengage the rollers of said container, said means including a movable track carrying plate associated with said vehicle, together with rotatable corner posts upon which said plate is movably mounted.

5. A freight handling apparatus, including a vehicle, a plurality of sliding tracks carried by said vehicle for engaging rollers carried by a container to permit said container to be moved on said tracks into and out of said vehicle, and means for vertically moving said tracks to engage or disengage the rollers of said container, said means including a movable track carrying plate associated with said vehicle, together with rotatable corner posts upon which said plate is movably mounted, said corner posts and plate including co-operating threaded portions whereby rotation of said posts will vertically move said plate.

6. A freight handling apparatus, including a vehicle, a plurality of sliding tracks carried by said vehicle for engaging rollers carried by a container to permit said container to be moved on said tracks into and out of said vehicle, means for vertically moving said tracks to engage or disengage the rollers of said container, said means including a movable track carrying plate associated with said vehicle, together with rotatable corner posts upon which said plate is movably mounted, said corner posts and plate including co-operating threaded portions whereby rotation of said posts will vertically move said plate, and means on said vehicle for simultaneously operating said posts in unison.

7. A freight handling apparatus, including a vehicle, a plurality of sliding tracks carried by said vehicle for engaging rollers carried by a container to permit said container to be moved on said tracks into and out of said vehicle, means for vertically moving said tracks to engage or disengage the rollers of said container, said means including a movable track carrying plate associated with said vehicle, together with rotatable corner posts upon which said plate is movably mounted, said corner posts and plate including co-operating threaded portions whereby rotation of said posts will vertically move said plate, and means on said vehicle for simultaneously operating said posts in unison, said vehicle including foldable side supporting means for retaining said vehicle against tilting.
